(57) **CLAIM**

The ornamental design for a solar tracker drive apparatus, as shown and described.

DESCRIPTION

FIG. 1 is a perspective view of a solar tracker drive apparatus showing my new design;

FIG. 2 is a front elevation view thereof;

FIG. 3 is a back elevation view thereof;

FIG. 4 is a first side view thereof;

FIG. 5 is a second side view thereof;

FIG. 6 is a top plan view thereof; and,

FIG. 7 is a bottom plan view thereof.
